Merchant and Keane

UNITED STATES PATENT OFFICE.

CLARENCE A. BERKINS, OF MINNEAPOLIS, MINNESOTA.

HYDROCARBON BURNER.

Application filed October 28, 1922. Serial No. 597,454.

To all whom it may concern:

Be it known that I, CLARENCE A. BERKINS, a citizen of the United States, residing at Minneapolis, in the county of Hennepin and State of Minnesota, have invented certain new and useful Improvements in Hydrocarbon Burners; and I do hereby declare the following to be a full, clear, and exact description of the invention, such as will enable others skilled in the art to which it appertains to make and use the same.

My invention relates to hydro-carbon burners adapted for general use in furnaces, boilers, stoves and the like, and has for its object to simplify the construction and improve the operation of such devices.

Generally stated, the invention consists of the novel devices and combinations of devices hereinafter described and defined in the claims.

The commercial form of this improved burner is illustrated in the accompanying drawings; wherein like characters indicate like parts throughout the several views.

Referring to the drawings:

Fig. 1 is a plan view of the improved burner; some parts being broken away; and

Fig. 2 is a vertical section taken on the line 2—2 of Fig. 1 and showing the burner set on the grate of a boiler or furnace.

This improved burner comprises four main elements, towit: a base member 3 of box-like form, a plate member 4 mounted as a cover for said base, a goose neck air delivery tube 5, and a generating cone 6. The box-like base 3 has a transverse partition 7 that divides the same into an air intake chamber 8 and a dead air chamber 9. The cover plate 4 is preferably flanged so that it sets in proper position on the top of the box-like base 3, and above the dead air chamber 9 it is formed with a generating bowl 10 having at its axis an upstanding cone 11 that preferably rises slightly above the rim of the bowl.

The bottom surface of the bowl is formed with circumferentially and radially spaced upstanding combined heat-radiating and gas-deflecting pins 12 preferably cast as tapered lugs integral with said bowl and cover plate. An oil or fluid fuel supply pipe 13 leads upward through the compartment 9 and is tapped into the cone 11. The upper end of this pipe 13 communicates with a smaller oil delivery pipe, or pipe section 14 that is threaded into the top of the cone 11

and projects above the same to afford a contracted oil delivery nozzle.

The generating cone 6 is a hollow structure, into the apex of which is screwed the threaded upper portion of the pipe section 14, thereby supporting the generating cone 6 free for vertical adjustments in respect to the bowl 10 and with the inner surface of said generating cone exposed to the hot gases that will rise within the interior thereof.

The goose-necked or curved air delivery tube 5 is preferably a cast shell tapered or decreased in diameter in a direction from its receiving toward its delivery end. The receiving end of said air tube 5 is seated in a closely fitting opening in the cover plate 4 and receives from the air compartment 8. The somewhat contracted downturned delivery end of said air pipe 5 concentrically surrounds the generating cone 6 and terminates above the top or rim of the bowl 10. To detachably hold the air tube 5 in the position just stated, it is provided at its receiving end with an outstanding flange 15 having notches through which screws 16 are passed and screwed into the cover plate 4.

In applying the burner above described to the grate of a boiler, heater or furnace, the upper end of the box-like base 3 is placed directly on the base *y* and all portions of the grate outward of the base are closed against the passage of air therethrough by suitable means, such as bricks *y'* or the like.

For safety, the bowl 10, below its rim and at one side, is provided with an overflow port 17 from which an oil discharge pipe 18 leads to a suitable point of discharge.

For controlling the supply of fluid fuel to the burner and for cutting the supply of fluid fuel off in case the flame should go out, there should be an overflow of oil into the bowl 10, and valve mechanism in connection, such as disclosed in my pending application Serial No. 508,060, filed October 17, 1921, and allowed July 19, 1922, may be employed, but such connection need not here be further considered.

Operation.

The operation of the burner described will be substantially as follows:

This burner will burn almost any kind of fluid fuel, but is intended especially for the lower grade hydro-carbons, such as fuel oil, distillate or low grade kerosene. The

fluid fuel delivered through the pipes 13-14 will overflow at the apex of the generating cone 6 and will trickle downward over the external steps or annular shoulders of said cone until it is vaporized, and when the burner is hot, the vaporization will be very rapid and will be complete before the fuel reaches the bottom of the generating cone. The air drawn in by natural draught or otherwise through the chamber 8 and air tube 5 will be delivered downward around the generating cone and into the bowl and through the spaces between the pins 12. When the burner is in action, the pins 12 will be kept very hot so that they readily assist in maintaining the combustion and making the combustion complete. In fact, the said pins act not only as heat radiators but as deflectors to break up the stream of commingled air and hydrocarbon vapor or the flames resulting therefrom as they are drawn downward, outward and upward through or over the bowl 10. Thus, the most complete combustion is insured. The taper of the tube 5 toward its delivery end produces the most rapid travel of the air at the point of delivery against the hydrocarbon vapors and further intensifies the combustion. By vertical adjustments of the generating cone 6, it may be set in respect to the delivery end of the air tube so as to give the most efficient flame. When the flame is low, it will come into direct contact only with the upper ends of the pins 12, but when the flame is at its greatest intensity, it will completely embrace the said pins and be dashed against the bottom of the bowl. Even when the flame is low, however, the numerous pins will be kept hot enough to

insure re-ignition in case the flame should be momentarily puffed out.

In practice, I have found that this burner is capable of producing complete combustion, both when the flame is at its greatest intensity and when it is cut down to a very small flame amounting substantially to a pilot light, and, of course, it will burn with like efficiency at intermediate points of intensity. This, itself, is a highly important feature, for it eliminates the necessity of the independent pilot light and makes it possible to graduate the flame to the heat required without resorting to the usual expedient of intermittently lighting and turning off the main flame. Moreover, the burner described is of very simple construction and low cost while, at the same time, efficient.

What I claim is:

1. A burner of the kind described comprising a bowl having on its bottom a plurality of laterally spaced upstanding combined heat-radiating and gas-deflecting pins or projections, a generating cone positioned centrally above the bowl, means for delivering fluid fuel to the upper portion of said generating cone, and an air pipe having a delivery end surrounding said cone and arranged to deliver air downward and between said pins.

2. The structure defined in claim 1 in further combination with an air chamber located below the plane of the bottom of said bowl, said air pipe having its receiving end extended into and communicating with said air chamber at one side of said bowl. 75

In testimony whereof I affix my signature.

CLARENCE A. BERKINS.
